UNITED STATES PATENT OFFICE.

JOSEPH A. BENEDICT, OF CHICAGO, ILLINOIS.

RECEPTACLE.

Application filed January 4, 1921. Serial No. 434,968.

To all whom it may concern:

Be it known that I, JOSEPH A. BENEDICT, a citizen of the United States of America, and a resident of Chicago, county of Cook, 5 and State of Illinois, have invented certain new and useful Improvements in Receptacles, of which the following is a specification.

This invention has for its object to provide certain new and useful improvements in boxes or receptacles particularly adapted for the storage of stock on shelves.

The particular object of the invention is to provide a closure for such receptacles 15 which will permit the same to be fully opened for access without drawing the box outwardly from the shelf for this purpose.

The invention is seen to be illustrated in the accompanying drawings, in which—

20 Fig. 1 is a perspective view of a receptacle constructed in accordance with the invention;

25 Fig. 2 is a fragmentary detail vertical longitudinal section of the same on the line 2—2 of Fig. 1;

Fig. 3 is a fragmentary detail vertical longitudinal section of the same showing the closure partly down in open position.

30 The receptacle may be made of any suitable material and is generally, and most conveniently, of rectangular cross-section, one end thereof being normally entirely open.

35 The top wall A of the receptacle projects slightly forward of the front edges of the side and bottom walls and the said projecting portion is provided in its lower face with a longitudinal groove B, the rear wall of which is preferably flush with the front 40 edges of the side walls.

Hinged in any suitable manner to the front edge of the bottom wall C of the receptacle is one part or plate D of the receptacle closure which consists of the parts D 45 and E hinged together along a line or pivotal axis which is parallel with the top and bottom walls of the receptacle. The said hinged connection between the plates D and E is such as to permit the same to become 50 disposed angularly relatively to each other, as shown in Fig. 3, so that the inner portion of the angle formed thereby opposes the open end of the receptacle. The plates D and E are of such dimensions relatively to the mouth of the receptacle so that the side edge portions of said plates are adapted to

push against the front edges of the side walls, and so that when they are disposed as shown in Fig. 2, the free edge of the plate E will engage in the groove B in the top 60 wall A. Thus, when said plates D and E are held flush with each other and against relative pivotal movement and the free edge of the plate E is engaged in the groove B, the said closure plate will be maintained in 65 closed position.

In order to effect such closure and maintain the receptacle firmly closed the plate E is provided with a latch member comprising the plate F suitably secured to said plate 70 E preferably about midway between the side edges thereof and adjacent its hinged connection with the plate D. A lever G is pivotally secured to the plate F and is adapted to engage the projecting spring tongue H 75 struck from or otherwise secured to a plate I suitably secured to the plate D midway between the side edges thereof and adjacent its hinged connection with the plate E. The lever G spans the hinged connection between 80 the plate D and E and when engaged with the spring tongue H serves to hold the plates D and E firmly flush with each other.

The hinge connection between the plate D and the bottom wall C of the receptacle 85 is such as to permit said plate D to drop down below and hang substantially vertically from said bottom wall C, thus causing the open end of the receptacle to be completely exposed to view and to permit the contents of the receptacle to be very readily removed without necessitating outward movement of the receptacle from the shelf or other support therefor. In effecting closure of the receptacle the plates D and E 90 are moved to substantially the relative position shown in Fig. 3, and upon continued pivotal movement of the plate D relative to the bottom wall C in an upward direction the free edge of the plate E will strike 100 the front edges of the side walls of the receptacle and thereupon further continued movement of the plate D in the same direction will cause the said free edge of the plate E to move continuously upwardly until it is engaged in the groove B. At this time the plates D and E will be flush with each other and thereupon a pivotal movement of the latch lever G to engage the spring tongue H will lock the plates D and 110 E in said flush position and against pivotal movement relative to each other, thus hold-

ing them firmly in position to complete closure of the receptacle. In order to open the receptacle it is only necessary to turn the latch lever G out of engagement with the tongue H, whereupon the closure will drop by gravity to its lowermost position, as will be obvious.

While I have shown the preferred embodiment of the invention in the accompanying drawings, it will be understood, of course, that such embodiment may be changed and varied in details of construction without departing from the invention as defined in the appended claim.

15 I claim as my invention:

A receptacle having side walls and a top and bottom wall, said receptacle open at one end and said top and bottoms projecting beyond the ends of the side walls, there being 20 a groove in the lower face of the projecting end portion of the top wall, a closure for said open end comprising two plates, one thereof hinged to the projecting end portion of the bottom wall and the other 25 thereof hinged along one edge to the free end of the first-named plate, the combined

length of said plates being such that when flush with each other the free edge of the last-named plate is adapted to engage in said groove, the side edge portions of said plates adapted to abut against the ends of the side walls of said receptacle when in closed position, said plates adapted to be angularly disposed with relation to each other as they are moved to closed position and brought flush with each other as the free end of the second-named plate strikes the ends of the side walls to thereby project said free end into said groove, and means for maintaining said closure member in said position comprising a latch member pivotally secured to one of said plates, a coacting latch element rigidly mounted on the other plate and adapted to engage the free end portion of said pivoted member as the latter is turned to position spanning the hinge connection between said plates, to thereby coact with said ends of said side walls to prevent relative pivotal movement of said plates and disengagement of said free end of said second plate from said groove.

JOSEPH A. BENEDICT.
